(57) **CLAIM**

The ornamental design for a ratchet lever hoists, as shown and described.

DESCRIPTION

The file of this patent contains at least one drawing/photograph executed in color. Copies of this patent with color drawing(s)/photograph(s) will be provided by the Office upon request and payment of the necessary fee.

1.-3. Ratchet lever hoists

1.1 : Left

1.2 : Right

1.3 : Front

1.4 : Back

1.5 : Top

1.6 : Bottom

1.7 : Perspective

1.8 : Perspective

1.9 : Perspective

1.10 : Perspective

2.1 : Left

2.2 : Right

2.3 : Front

2.4 : Back

2.5 : Front

2.6 : Bottom

2.7 : Perspective

2.8 : Perspective

2.9 : Perspective

2.10 : Perspective

3.1 : Left

3.2 : Right

3.3 : Front

3.4 : Back

3.5 : Top

3.6 : Bottom

3.7 : Perspective

3.8 : Perspective

3.9 : Perspective

3.10 : Perspective

The handle is shown in an alternate position of it being outside of the lever arm in FIGS. **1.8, 1.10, 2.8, 2.10, 3.8** and **3.10** for convenience of illustration.
